UNITED STATES PATENT OFFICE.

JOHN R. HAMILTON, OF YONKERS, NEW YORK, ASSIGNOR TO SYPHO-CHEMICAL SPRINKLER CORPORATION, OF CROTON-ON-HUDSON, NEW YORK, A CORPORATION OF NEW YORK.

AUTOMATIC FIRE-EXTINGUISHING APPARATUS.

1,264,394.

Specification of Letters Patent. Patented Apr. 30, 1918.

Application filed October 4, 1915. Serial No. 53,877.

To all whom it may concern:

Be it known that I, JOHN R. HAMILTON, a citizen of the United States, residing at Yonkers, county of Westchester, State of New York, have made a certain new and useful Invention Relating to Automatic Fire-Extinguishing Apparatus, of which the following is a specification, taken in connection with the accompanying drawings, 10 which form part of the same.

This invention relates especially to chemical fire extinguishing apparatus comprising a distributing system normally charged with extinguishing liquid and provided with automatic or other extinguishing devices arranged at various points around the building to be protected. A supplemental supply of extinguishing liquid is connected to the distributing system and may comprise 15 any suitable gaseous pressure tank such as a chemical mixing tank and coöperating chemical mixing devices to discharge acid or other pressure producing chemical into the tank. A suction actuating pipe or connection may communicate with the mixing devices to operate them and a priming actuating tank may be arranged in connection with the distributing system at any suitable point so as to supply liquid thereto and also 20 to effect the operation of the mixing devices on the fire emergency discharge of liquid from the system. The actuating pipe for this purpose may extend adjacent the top of a suitable suction chamber formed within 25 or connected with the actuating tank and in order to secure the emergency operation of the system in case of slow leakage therefrom a suitable vacuum chamber may be provided in connection with the suction 30 chamber and may if desired communicate therewith at its lower end so that under slow leak conditions a pressure reduction or unbalanced fluid pressure condition is produced in the vacuum chamber. Any suitable retarding device may be arranged between the suction chamber and vacuum chamber so as to restrain or cut off communication between them until a predetermined condition or pressure reduction has 35 taken place whereupon the retarding device

is automatically released and a sudden suction or other fluid impulse acts through the actuating connection so as to bring the chemical mixing device or the like into emergency action and thereby call attention to 55 the condition of the apparatus through suitable alarm devices, if desired.

In the accompanying drawings showing in a somewhat diagrammatic way several 60 illustrative embodiments of the invention.

Figure 1 is a vertical section through one form of apparatus.

Fig. 2 is a corresponding detail section showing a modified construction; and

Fig. 3 is an enlarged section showing still 65 another arrangement.

The distributing system may be of any desired construction and may comprise a supply pipe or riser 20 and connected distributing lines 17 supplying the distributing 70 devices, such as the automatic sprinkler heads 76 arranged at various points around the building to be protected. Any suitable extinguishing liquid may be normally contained in the distributing system and if desired 75 may be supplied thereto under a suitable moderate initial head or pressure by the use of an elevated priming or actuating tank 19 extending the desired distance above the upper part of the distributing system 80 and connected to the upper end 47 of the riser 20, if desired. A supplemental supply of extinguishing liquid is connected to the distributing system in any suitable way and may comprise the chemical mixing tank 18 85 containing a charge 22 of carbonate extinguishing liquid, for instance, the supply connection or riser 20 preferably extending below the check valve 77 into the mixing tank adjacent the bottom thereof and being 90 there provided with a suitable strainer 21 as is usual in this connection, so that when the coöperating chemical mixing devices or other means for producing gaseous pressure in the tank come into action the desired high 95 emergency pressure of 50 to 100 pounds or so per square inch is developed through chemical action in the tank so as to give a forcible discharge from the distributing devices in operation.

The chemical mixing devices may, if desired, comprise a suitable casing 23 mounted on the mixing tank and communicating therewith through the opening 29, this casing being normally tightly closed by a removable cover, such as 51. One or more co-operating charges of sulphuric acid or other pressure producing chemical adapted to react with the liquid in the mixing tank are 10 contained in this casing and a desirable arrangement for holding and feeding these charges of chemical may comprise a supplemental acid or chemical chamber 24 supported in any desired way within the casing 15 and formed with a centrally arranged automatic pressure maintaining siphon comprising the discharge pipe 28 and the siphon bell 30 inclosing the upper end 31 of this discharge pipe so as to intermittently feed 20 the charge 67 of acid in this chamber into the mixing tank whenever the initial emergency pressure momentarily decreases under operating conditions. The siphon starting devices which may be of the type covered by the pending application of Everett L. Thompson, Jr., which has matured into Patent No. 1,206,173, granted November 28, 1916, may with advantage be arranged in the upper part of the casing and may 25 comprise a removable siphon chamber 26 which is adapted to fit into a pocket 59 in the upper portion of the supplemental chemical chamber 24. This removable casing which may also be formed of sheet lead or other 30 suitable inert material may have cylindrical sides and conical ends and intermediate partitions which may be conveniently stamped or otherwise given the same conical shape and connected to the sides by lead 35 burning or other methods. A starting chamber may be formed in this device to normally contain a starting charge 65 of sulphuric acid or other pressure producing chemical and a siphon starting device 40 comprising the siphon discharge pipe 55 may be arranged in this chamber so that its upper end 54 is above the normal acid level 45 therein and is inclosed by the siphon bell 53 supported from the diaphragm below so as 50 to leave an annular passage 65 through which the acid may enter the siphon bell under operating conditions, a suitable filling and equalizing aperture 52 being preferably provided in the upper end of this 55 chamber. A suction siphon chamber 64 may be formed in this device and an automatically discharging siphon may be arranged to deliver the acid therefrom into the mixing tank, this siphon comprising the 60 siphon bell 56 supported within the removable starting device so that acid can enter it and flow down the automatic discharge siphon pipe 27 which may as indicated be arranged axially within the supplemental 65 chamber 24 and permanently connected thereto. A suction coupling 61 of light lead pipe or other suitable material may be arranged between this suction siphon chamber 64 and the union 63 on the suction actuating pipe or connection 46 extending to the 70 actuating tank so that on the fire emergency discharge of liquid from the system a suction impulse is caused in this pipe and chamber 64 so as to simultaneously operate the starting siphon and deliver the starting 75 charge 65 into the chamber 64, while at the same time this suction tends to draw the charge 66 down inside the siphon bell 56 so that operation of the automatically discharging siphon is thereby prevented until 80 the starting charge is delivered and the suction broken through this starting siphon. It will thus be seen that the starting device 26 may be readily removed for inspection or 85 repairs by releasing the coupling 63 and when replaced by being inserted into the pocket 59 it is operative without the necessity of making a tight joint with this part, since the acid forms a liquid seal between 90 this pocket and the starting device which 95 is fully effective in this connection, it being of course understood that the amount of space between these parts is considerably exaggerated in the drawings for the sake of clearness. It is also understood that suitable equalizing or venting apertures such as the pin-hole or other small vent 60, may be formed in any suitable part of the supplemental pressure chamber and that a similar pin-hole or other equalizing aperture 62 100 may be formed in the suction coupling or other part of the suction siphon chamber or its connections.

The suction actuating pipe or connection 46 may as indicated extend up through the 105 supply pipe 20 so that its upper end 31 is adjacent the top of a suitable shell or cylindrical casing 35 forming the suction chamber 32 within the priming tank 19. If desired a suitable vacuum chamber 49 may be 110 formed concentrically about this suction chamber by the concentric casing 34 supported in connection therewith, the lower 115 ends of these chambers being in open communication since the bottoms 44, 45 of these casings may be left open as indicated. Any suitable retarding device preferably of an 120 automatically releasing character may be used in the connection which is preferably provided between the upper ends of the suction and vacuum chambers, and if desired a liquid retarding device of this character 125 may be used in the form of a U-tube 37 extending through the casing 35 and having its upper ends 38, 39 extending adjacent the tops of these chambers so that under conditions of slow leak from the distributing system the vacuum which tends to form in

the vacuum chamber is substantially maintained therein until this retarding device is automatically released and allows free communication between these chambers so that 5 the suction impulse is thereupon transmitted through the suction actuating connection communicating with the suction chamber. If desired also a suitable vented reservoir 48 may be arranged in connection with, or if 10 desired, concentrically around the vacuum chamber, and this reservoir may have a vent or overflow waste pipe 36 connected therewith adjacent its upper portion and may have an automatically closing vent valve 40 15 arranged in connection with this vent preferably so as to be normally open, but so as to quickly close on any large or substantial flow of liquid past the valve.

On filling the distributing system the liquid 20 may be forced up into the same through the supply pipe 20, the liquid thus rising through the vacuum and suction chambers and reservoir at substantially the same height since the air is free to escape through the 25 open vent and through the empty U-tube retarding device so that air in the vacuum chamber can thus be discharged through the suction actuating pipe. Then when the top of the liquid reaches the end 38 of the U-tube in 30 the vacuum chamber this tube fills with liquid and any further liquid supply to this chamber raises the liquid level 41 therein thereby compressing slightly the air which is trapped in the upper part of this chamber and the 35 liquid can rise in the inner suction chamber 32 so that the liquid level 33 therein may nearly reach the upper end of the suction actuating pipe 31. The liquid in the outer reservoir 48 may rise until it begins to be 40 discharged from the vent or overflow pipe 36 which indicates that sufficient liquid has been supplied to the system to fill the different chambers to substantially the points indicated in Fig. 1 and under fire emergency 45 conditions the rapid discharge of liquid from the distributing system causes a considerable pressure reduction or suction impulse which acts through the connection or pipe 46 to operate the starting siphon and 50 mixing devices as has been described. This causes the desired emergency discharge pressure of 50 to 100 pounds per square inch within the mixing tank and may operate any suitable alarm devices to call attention to the 55 apparatus, a simple electrical alarm being somewhat diagrammatically indicated as comprising a pressure pipe 80 extending up from the mixing tank 18 to the diaphragm chamber 81 within which a flexible metallic 60 or other diaphragm 82 may be mounted so as to be normally out of engagement with the electric contacts 83 which may be in circuit with a battery 85 or other source of electricity and with an electric bell or other

alarm 84. This alarm is thus operated as 65 soon as the pressure forces the diaphragm up into contact with the electric contacts 83 to close this alarm circuit. Under slow leak conditions where the liquid leaks out of the system a drop or two at a time the discharge 70 from a simple actuating tank would be too slow to properly operate the mixing devices in this way, but under these conditions the retarding device allows a predetermined suction or vacuum to take place in the vacuum 75 chamber before the restraining action of the retarding device is released to cause a sudden suction impulse of sufficient intensity to operate these starting or chemical mixing devices. With the illustrative arrangement 80 indicated in Fig. 1 the liquid would slowly descend in the suction chamber and reservoir to about the level 43 while the descent of the liquid in the vacuum chamber would be very much less, indicated somewhat diagrammatically at 42, the air within this vacuum chamber being correspondingly reduced in pressure so that a considerable 85 vacuum is thus created which serves to draw the liquid down in the arm 39 of the U-tube 90 retarding device so that it would reach about the level 50 therein. When, however, still further slow discharge of the liquid occurs the further increase in the suction pressure in the vacuum chamber finally suddenly 95 draws the liquid up through the arm 38 of the U-tube which when this sealing liquid is withdrawn no longer acts as a retarding device, but allows the air from the suction chamber to quickly pass through this U-tube 100 into the vacuum chamber creating a sudden suction or pressure reduction within the suction chamber and connected suction actuating pipe of sufficient intensity to operate any suitable form of starting siphon or other 105 chemical mixing or alarm devices. In this arrangement the vented reservoir also contributes to this action because it allows liquid from the bottom of the vacuum chamber to enter this reservoir while the displaced air can escape through the vent and thus minimize the equalization of the liquid between the lower ends of the vacuum and suction chambers which is to some extent retarded by the inertia of these bodies of 110 liquid.

Another arrangement of suction and cooperating vacuum chambers is indicated in Fig. 2 as comprising a central suction chamber 32 and the encircling vacuum chamber 74 120 which communicates at its lower end with the suction chamber preferably through a restricted passage 72. On filling the system through the supply pipe 20 the liquid naturally rises to about the level indicated at 69 125 in the vacuum chamber and to about the level 70 in the suction chamber where it tends to discharge through the upper end 31

of the suction actuating pipe 46. Under slow leak conditions the liquid tends to fall to about the point 71 in the vacuum chamber where it is held by the resulting partial vacuum caused by the exhaustion of the air above while in the suction chamber which is vented by the open suction actuating pipe the liquid can fall to about the point 43 before the liquid retarding device or seal in the 5 ¹⁰ U-tube 37 blows through and allows the quick equalization of these unbalanced fluid pressures which causes a sudden suction impulse through the actuating pipe of sufficient intensity to operate any suitable form of chemical mixing or other emergency devices connected with the system. The inertia of the liquid remaining in the suction and vacuum chambers prevents the quick equalization of the unbalanced pressure on top of 15 these liquid columns and this is further retarded or prevented by the restricted character of the passage 72 at the bottom of these chambers.

A still further arrangement is indicated 20 in Fig. 3 as comprising an enlarged priming or actuating tank 1 which may be mounted at the top of the system and which may be formed with an enlargement 10 at its upper portion. This actuating tank may be provided with a differential valve seat 12 having 25 a vent channel 5 communicating with the ball check vent 6 in which the ball valve 7 is normally in open position against the stop pin 15. A suitable float casing 3 may have 30 a buoyant air space 4 adjacent its lower portion and be provided with a valve flange 11 coöperating with the differential valve seat and normally held down tightly thereon by the static pressure of the liquid in the tank 35 which is effective throughout the area above the differential valve seat and which forms a self-releasing retarding device. The system may be filled by forcing the liquid up 40 in the actuating tank 1 while the float casing 45 is held down in the indicated position in any suitable way, as for instance, by a suitable suction pump connected to the ball valve vent 6 and the liquid thus rises inside the casing in the enlarged upper portion 10 of the actuating tank and also through the 50 openings or passages 86 into the casing until it is discharged from the ball check waste vent 8 having the ball valve 9 normally in open position against the stop pin 15. The 55 level of the liquid inside the casing is preferably somewhat below the top 14 of the suction actuating pipe 2 communicating with the mixing devices in any desired way. Under slow leak conditions the liquid gradually descends, passing down inside the float casing or outside it through suitable ports or passages 86 until it reaches substantially the 60 level indicated by the dot and dash line when the static pressure of this liquid is no longer sufficient to hold the valve flange 65

against the differential valve seat and thereupon this retarding device is automatically released and the valve casing floats upward thereby creating a suction or partial vacuum within the air space 13 in the top of this 70 casing so that the desired suction impulse acts through the acting pipe to bring the chemical mixing devices into operation if desired.

This invention has been described in connection with a number of illustrative embodiments, forms, arrangements, materials, proportions, sizes and parts of the apparatus, to the details of which disclosure the invention is not of course to be limited, since what is claimed as new and what is desired to be secured by Letters Patent is set forth in the appended claims.

1. In chemical fire extinguishing apparatus, a distributing system normally charged with extinguishing liquid and comprising distributing devices, a supplemental supply of extinguishing liquid connected to said system and comprising a mixing tank and chemical mixing devices to discharge pressure producing chemical into said mixing tank, a suction actuating connection communicating with said mixing devices to effect their operation, a priming actuating tank communicating with said distributing system and formed with a suction chamber with which said suction actuating connection communicates, a vacuum chamber communicating at its lower end with said suction chamber, a reservoir communicating at 90 its lower end with said vacuum chamber and having its upper portion vented to the air, a releasing retarding device between the upper ends of said suction chamber and vacuum chamber to resist pressure equalization between the upper parts of said vacuum chamber and suction chamber under slow leak conditions and to effect a sudden suction impulse through said actuating connection when the restraining action of said 95 retarding device is released.

2. In fire extinguishing apparatus, a distributing system normally charged with extinguishing liquid and comprising distributing devices, a supplemental supply of extinguishing liquid connected to said system and comprising devices to develop discharge pressure on said supply, a suction actuating connection communicating with said devices to effect their operation, a priming actuating tank communicating with said distributing system and formed with a suction chamber with which said suction actuating connection communicates, a vacuum chamber communicating at its lower end with said suction chamber, a reservoir communicating at its lower end with said vacuum chamber and having its upper portion vented to the air, a releasing retarding device between the upper ends of said suction 115 120 125 130

chamber and vacuum chamber to resist pressure equalization between the upper parts of said vacuum chamber and suction chamber under slow leak conditions and to effect a sudden suction impulse through said actuating connection when the restraining action of said retarding device is released.

3. In fire extinguishing apparatus, a distributing system normally charged with extinguishing liquid and comprising distributing devices, a supplemental supply of extinguishing liquid connected to said system and comprising devices to develop discharge pressure on said supply, a suction actuating connection communicating with said devices to effect their operation, a priming actuating tank communicating with said distributing system and formed with a suction chamber with which said suction actuating connection communicates, a vacuum chamber communicating with said suction chamber, a reservoir communicating at its lower end with said vacuum chamber and having its upper portion vented, a releasing retarding device between said suction chamber and vacuum chamber to resist pressure equalization between said vacuum chamber and suction chamber under slow leak conditions and to effect a sudden suction impulse through said actuating connection when the restraining action of said retarding device is released.

4. In fire extinguishing apparatus, a distributing system normally charged with extinguishing liquid and comprising distributing devices, a supplemental supply of extinguishing liquid connected to said system and comprising devices to develop discharge pressure on said supply, a suction actuating connection communicating with said devices to effect their operation, a priming actuating tank communicating with said distributing system and formed with a suction chamber with which said suction actuating connection communicates, a vacuum chamber communicating with said suction chamber, a reservoir communicating at its lower end with said vacuum chamber, a releasing retarding device between said suction chamber and vacuum chamber to resist pressure equalization between said vacuum chamber and suction chamber under slow leak conditions and to effect a sudden suction impulse through said actuating connection when the restraining action of said retarding device is released.

5. In fire extinguishing apparatus, a distributing system normally charged with extinguishing liquid and comprising distributing devices, a supplemental supply of extinguishing liquid connected to said system and comprising devices to develop discharge pressure on said supply, a suction actuating connection communicating with said devices to effect their operation, a priming actuating tank communicating with said distributing system and formed with a suction chamber with which said suction actuating connection communicates, a vacuum chamber communicating at its lower portion with said suction chamber, an automatically releasing liquid retarding device between the upper portions of said suction chamber and vacuum chamber and adapted to be filled with liquid in charging the system to resist pressure equalization between the upper parts of said vacuum chamber and suction chamber under conditions of slow leak from the distributing system until a predetermined pressure difference acting thereon releases said retarding device and thereby effects a sudden suction impulse through said actuating connection.

6. In fire extinguishing apparatus, a distributing system normally charged with extinguishing liquid and comprising distributing devices, a supplemental supply of extinguishing liquid connected to said system and comprising devices to develop gaseous discharge pressure on said supply to force liquid therefrom into said distributing system, a suction actuating connection communicating with said devices to effect their operation, a priming actuating tank communicating with said distributing system and formed with a suction chamber with which said suction actuating connection communicates, a vacuum chamber communicating at its lower portion with said suction chamber, an automatically releasing liquid retarding device between the upper portions of said suction chamber and vacuum chamber to resist pressure equalization between the upper parts of said vacuum chamber and suction chamber under conditions of slow leak from the distributing system until a predetermined pressure difference, acting thereon, releases said retarding device and thereby effects a sudden suction impulse through said actuating connection.

7. In chemical fire extinguishing apparatus, a distributing system normally charged with extinguishing liquid and comprising distributing devices, a supplemental supply of extinguishing liquid connected to said system and comprising a mixing tank and chemical mixing devices to discharge pressure producing chemical into said mixing tank, a suction actuating connection to effect

5. In fire extinguishing apparatus, a distributing system normally charged with extinguishing liquid and comprising automatic distributing devices, a supplemental supply of extinguishing liquid connected to said system and comprising devices to develop gaseous discharge pressure on said supply to force liquid therefrom into said distributing system, a suction actuating con- 60 tank, a suction actuating connection to effect the operation of said mixing devices, a priming actuating tank communicating with the upper part of said distributing system and formed with a suction chamber 125 with which said suction actuating connection communicates, a vacuum chamber communicating at its lower end with said suction chamber through a restricted passage, a releasing liquid retarding device between 65 130

- the upper ends of said suction chamber and vacuum chamber and adapted to resist pressure equalization between the upper parts of said vacuum chamber and suction chamber 5 under conditions of slow leak from the distributing system and to effect a sudden suction impulse through said actuating connection when the restraining action of said retarding device is released.
- 10 8. In chemical fire extinguishing apparatus, a distributing system normally charged with extinguishing liquid and comprising distributing devices, a supplemental supply of extinguishing liquid connected to said system and comprising a mixing tank and chemical mixing devices to discharge pressure producing chemical into said mixing tank, a suction actuating connection to effect the operation of said mixing devices, a 15 priming actuating tank communicating with the upper part of said distributing system and formed with a suction chamber with which said suction actuating connection communicates, a vacuum chamber communicating with said suction chamber through a restricted passage, a releasing liquid retarding device between said suction chamber and vacuum chamber and adapted to resist pressure equalization between said vacuum 20 chamber and suction chamber under conditions of slow leak from the distributing system and to effect a sudden suction impulse through said actuating connection when the restraining action of said retarding device is released.
- 25 9. In fire extinguishing apparatus, a distributing system normally charged with extinguishing liquid and comprising distributing devices, a supplemental supply of extinguishing liquid connected to said system and comprising devices to develop discharge pressure on said supply, a suction actuating connection to effect the operation of said devices, a priming actuating tank communicating with the upper part of said distributing system and formed with a suction chamber with which said suction actuating connection communicates, a vacuum chamber communicating with said suction chamber through a restricted passage, a releasing 30 retarding device between said suction chamber and vacuum chamber and adapted to resist pressure equalization between said vacuum chamber and suction chamber under conditions of slow leak from the distributing system and to effect a sudden suction impulse through said actuating connection when the restraining action of said retarding device is released.
- 35 10. In fire extinguishing apparatus, a distributing system normally containing extinguishing liquid and comprising distributing devices, a supplemental supply of extinguishing liquid connected to said system and comprising devices to force liquid from

said supplemental supply into said distributing system, a fluid suction actuating connection communicating with said devices to effect their operation, a vacuum chamber communicating with said distributing system to have a pressure change developed therein on the commencement of flow from said system, a U-tube liquid retarding device between said actuating connection and said vacuum chamber and adapted to be 70 filled with liquid in charging the system to resist pressure equalization under conditions of slow leak from the distributing system until the pressure change developed releases the restraining action of said retarding device thereupon allowing a sudden fluid impulse to be transmitted through said actuating connection.

11. In fire extinguishing apparatus, a distributing system normally containing extinguishing liquid and comprising distributing devices, a supplemental supply of extinguishing liquid connected to said system and comprising devices to force liquid from said supplemental supply into said distributing system, a fluid actuating connection communicating with said devices to effect their operation, a vacuum chamber communicating with said distributing system to have a pressure change developed therein 80 on the commencement of flow from said system and a liquid retarding device between said actuating connection and said vacuum chamber and adapted to be filled with liquid in charging the system to resist pressure 85 equalization under conditions of slow leak from the distributing system until the pressure change developed releases the restraining action of said retarding device thereupon allowing a sudden fluid impulse to be 90 transmitted through said actuating connection.

12. In fire extinguishing apparatus, a distributing system normally containing extinguishing liquid and comprising distributing devices, a supplemental supply of extinguishing liquid connected to said system and comprising devices to force liquid from said supplemental supply into said distributing system, a fluid actuating connection 110 communicating with said devices to effect their operation, a vacuum chamber communicating with said distributing system to have a pressure change developed therein on the commencement of flow from said system and a retarding device between said actuating connection and said vacuum chamber and adapted to be filled with liquid in charging the system to resist pressure equalization under conditions of slow leak from 115 the distributing system until the pressure change developed releases the restraining action of said retarding device thereupon allowing a sudden fluid impulse to be 120 transmitted through said actuating connection.

13. In chemical fire extinguishing apparatus, a distributing system normally charged with extinguishing liquid and comprising automatic distributing devices, a supplemental supply of extinguishing liquid connected to said system and comprising a chemical mixing tank and chemical mixing devices to discharge pressure producing chemical into said mixing tank, a fluid actuating connection communicating with said mixing devices to effect their operation, a priming actuating tank communicating with said distributing system and provided with actuating means tending to send a fluid impulse through said actuating connection and a self releasing retarding device normally restraining the action of said actuating means until said means can act with predetermined intensity to thereby transmit a sudden operating impulse under slow leak conditions after an undesirable amount of leakage from said system.

14. In fire extinguishing apparatus, a distributing system normally charged with extinguishing liquid and comprising automatic distributing devices, a supplemental supply of extinguishing liquid connected to said system and comprising devices to force liquid from said supplemental supply into said distributing system, a fluid actuating connection communicating with said devices to effect their operation, a priming actuating tank communicating with said distributing system and provided with actuating means tending to send a fluid impulse through said actuating connection and a self releasing retarding device normally restraining the action of said actuating means until said means can act with predetermined intensity to thereby transmit a sudden operating impulse under slow leak conditions after an undesirable amount of leakage from said system.

15. In fire extinguishing apparatus, a distributing system normally charged with extinguishing liquid and comprising distributing devices, a supplemental supply of extinguishing liquid connected to said system and comprising devices to force liquid from said supplemental supply into said distributing system, a fluid actuating connection communicating with said devices to effect their operation, actuating means tending to send a fluid impulse through said actuating connection and a self releasing retarding device normally restraining the action of said actuating means until said means can act with predetermined intensity.

16. In chemical fire extinguishing apparatus, a distributing system normally charged with extinguishing liquid and comprising automatic distributing devices, a supplemental supply of extinguishing liquid connected to said system and comprising a chemical mixing tank, chemical mixing de-

vices to discharge pressure producing chemical into said mixing tank, a suction actuating connection communicating with said mixing devices to effect their operation, a priming actuating tank communicating with said distributing system and formed with a suction chamber within which said suction actuating connection extends adjacent the top thereof, a vacuum chamber encircling said suction chamber and communicating at its lower end therewith, a reservoir outside of said vacuum chamber and communicating at its lower end therewith and having its upper portion communicating with an overflow vent pipe, a normally open vent valve between said reservoir and vent and automatically closing on flow of liquid, a U-tube liquid retarding device between the upper ends of said suction chamber and vacuum chamber to be filled with liquid in charging the system and to resist pressure equalization between the upper parts of said vacuum chamber and suction chamber under slow leak conditions and thereby effect a sudden suction impulse through said actuating connection when the sealing liquid is forced out of said retarding device to release its restraining action.

17. In chemical fire extinguishing apparatus, a distributing system normally charged with extinguishing liquid and comprising distributing devices, a supplemental supply of extinguishing liquid connected to said system and comprising a chemical mixing tank, chemical mixing devices to discharge pressure producing chemical into said mixing tank, a suction actuating connection communicating with said mixing devices to effect their operation, a priming actuating tank communicating with said distributing system and formed with a suction chamber within which said suction actuating connection extends adjacent the top thereof, a vacuum chamber encircling said suction chamber and communicating at its lower end therewith, a reservoir outside of said vacuum chamber and communicating at its lower end therewith and having its upper portion communicating with an overflow vent, a normally open vent valve between said reservoir and vent and automatically closing on flow of liquid, a liquid retarding device between the upper ends of said suction chamber and vacuum chamber to be filled with liquid in charging the system and to resist pressure equalization between the upper parts of said vacuum chamber and suction chamber under slow leak conditions and thereby effect a sudden suction impulse through said actuating connection when the sealing liquid is forced out of said retarding device to release its restraining action.

18. In chemical fire extinguishing apparatus, a chemical mixing tank and coöperat-

ing siphon mixing devices comprising a casing, a supplemental chemical pressure chamber mounted in said casing and provided with a pocket in its upper portion and a discharge pipe projecting into said pocket and extending below said chamber, a supplemental discharge siphon in said chamber comprising a discharge passage arranged concentrically around said discharge pipe and a siphon bell inclosing said discharge passage, a removable siphon starting device in said casing and fitting within said pocket and comprising a suction siphon chamber having cylindrical lead sides and a coupling connected therewith and having a detachable union adjacent the inner surface of said casing, said siphon chamber being provided with a siphon bell extending over the top of said discharge pipe and containing a charge 20 of acid making a liquid seal therefor within said pocket, said siphon chamber having a diaphragm to support a starting charge of acid in its upper portion, a starting siphon extending through said diaphragm and a 25 vented upper end, the ends and diaphragm of said siphon chamber being formed of lead of substantially similar conical contour and secured to its cylindrical lead sides.

19. In chemical fire extinguishing apparatus, a chemical mixing tank and coöperating siphon mixing devices comprising a casing, a supplemental chemical pressure chamber mounted in said casing and provided with a pocket in its upper portion and a discharge pipe projecting into said pocket and extending below said chamber, a supplemental discharge siphon in said chamber comprising a discharge passage arranged around said discharge pipe and a siphon bell inclosing said discharge passage, a removable siphon starting device in said casing and fitting within said pocket and comprising a siphon chamber, said siphon chamber being provided with a siphon bell 40 extending over the top of said discharge pipe and containing a charge of acid making a liquid seal therefor within said pocket, said siphon chamber having a diaphragm to support a starting charge of acid in its 45 upper portion, a starting siphon extending through said diaphragm and a vented upper end.

20. In chemical fire extinguishing apparatus, a chemical mixing tank and coöperating siphon mixing devices comprising a casing, a supplemental chemical pressure chamber mounted in said casing and provided with a pocket in its upper portion and a discharge pipe projecting into said pocket, a supplemental discharge siphon in said chamber comprising a discharge passage arranged around said discharge pipe and a siphon bell inclosing said discharge passage, a removable siphon starting device 60 in said casing and fitting within said pocket

and comprising a siphon chamber, said siphon chamber being provided with a siphon bell extending over the top of said discharge pipe and containing a charge of acid making a liquid seal therefor within 70 said pocket.

21. In chemical fire extinguishing apparatus, a chemical mixing tank and coöperating siphon mixing devices comprising a casing, a chemical chamber mounted in said 75 casing and provided with a pocket in its upper portion and a discharge pipe, projecting into said pocket, a siphon discharge device in said chamber, a removable siphon chamber in said casing and fitting within 80 said pocket and provided with a suction bell extending over the top of said discharge pipe and containing a charge of acid making a liquid seal within said pocket around said chamber.

22. In chemical fire extinguishing apparatus, a chemical mixing tank and coöperating siphon mixing devices comprising a casing, a chemical chamber mounted in said 90 casing and provided with a pocket in its upper portion and a discharge pipe projecting into said pocket, a discharge device in said chamber, a removable siphon chamber in said casing and fitting within said 95 pocket and provided with a suction member extending over the top of said discharge pipe and containing a charge of acid making a liquid seal within said pocket around said chamber.

23. In fire extinguishing apparatus, a distributing system normally containing fluid, a device adapted to be operated under the fire emergency conditions of said system, a fluid actuating connection communicating with said device to effect its operation, actuating means connected to said system and tending to send a fluid impulse through said actuating connection on movement of fluid in said system and a self-releasing retarding device normally restraining the action 100 of said actuating means under slow leak conditions until said means can act with sufficient intensity to thereupon transmit an operating impulse to said device under slow leak conditions after an undesirable amount 105 of leakage from said system.

24. In fire extinguishing apparatus, a distributing system normally containing extinguishing liquid, a device adapted to be operated under the emergency conditions of said 120 system, a fluid actuating connection communicating with said device to effect its operation, actuating means connected to said system and tending to send a fluid impulse through said actuating connection on movement of fluid in said system and a retarding device normally restraining the action of said actuating means under slow leak conditions until said means can act with sufficient intensity to thereupon transmit an 125 130

operating impulse to said device under slow leak conditions after an undesirable amount of leakage.

25. In fire extinguishing apparatus, a distributing system normally containing fluid, a device to be operated to supply extinguishing fluid to said system, actuating means connected to said device to effect its operation and tending to cause a fluid impulse 5 on escape of fluid from said system and a self-releasing retarding device comprising a liquid seal normally restraining the action of said actuating means under slow leak conditions until said means can act with sufficient intensity to thereupon transmit an operating impulse to said device under slow leak conditions after an undesirable amount of leakage from said system.

26. In fire extinguishing apparatus, a distributing system normally containing fluid, a device to be operated in connection with said system, actuating means connected to said device to effect its operation and tending to cause a fluid impulse from said system and a retarding device comprising a body of liquid normally restraining said actuating means under slow leak conditions until said means can act with sufficient intensity to thereupon transmit an operating impulse to said device under slow leak conditions after an undesirable amount of leakage from said system.

27. In fire extinguishing apparatus, a priming actuating tank adapted to be connected with a distributing system and formed with a suction chamber with which a suction actuating connection is adapted to communicate, a vacuum chamber communicating adjacent its lower end with said suction chamber, a reservoir communicating adjacent its lower end with said vacuum chamber and having its upper portion vented to the air, a U-tube retarding liquid connection device between said suction chamber and said vacuum chamber and adapted to be normally filled with liquid in charging the system to resist pressure equalization under conditions of slow leak from the distributing system until the pressure change developed releases the restraining action of said retarding liquid connection and thereupon allows a sudden fluid impulse to be generated in said suction chamber.

28. In fire extinguishing apparatus, an actuating tank adapted to be connected with a distributing system and formed with a suction chamber with which a suction actuating connection is adapted to communicate, a vacuum chamber communicating adjacent its lower end with said suction chamber, a reservoir communicating adjacent its lower end with said vacuum chamber, a retarding device between said suction chamber and said vacuum chamber to resist pressure

equalization under conditions of slow leak from the distributing system until the pressure change developed releases the restraining action of said retarding device and thereupon allows a sudden fluid impulse to be generated in said suction chamber.

29. In fire extinguishing apparatus, an actuating tank adapted to be connected with a distributing system and formed with a suction chamber with which a suction actuating connection is adapted to communicate, a vacuum chamber communicating adjacent its lower end with said suction chamber, a retarding device between said suction chamber and said vacuum chamber to resist pressure equalization under conditions of slow leak from the distributing system until the pressure change developed releases the restraining action of said retarding device and thereupon allows a sudden fluid impulse to be generated in said suction chamber.

30. In fire extinguishing apparatus, an actuating tank adapted to be connected with a distributing system and formed with a suction chamber with which a suction actuating connection is adapted to communicate, a vacuum chamber communicating adjacent its lower end with said suction chamber, a reservoir communicating adjacent its lower end with said vacuum chamber, a U-tube retarding passage between said suction chamber and said vacuum chamber and adapted to be normally filled with liquid to thereupon resist pressure equalization under conditions of slow leak from the distributing system until the pressure change developed releases the restraining action of said retarding device and thereupon allows a sudden fluid impulse to be generated in said suction chamber.

31. In fire extinguishing apparatus, an actuating tank adapted to be connected with a distributing system and formed with a suction chamber with which a suction actuating connection is adapted to communicate, a vacuum chamber communicating adjacent its lower end with said suction chamber, a U-tube retarding passage between said suction chamber and said vacuum chamber and adapted to be normally filled with liquid to resist pressure equalization under conditions of slow leak from the distributing system until the pressure change developed releases the restraining action of said retarding device and thereupon allows a sudden fluid impulse to be generated in said suction chamber.

32. In fire extinguishing apparatus, an actuating tank adapted to be connected with a distributing system and formed with a suction chamber with which a suction actuating connection is adapted to communicate, a vacuum chamber communicating adjacent its lower end with said suction chamber, a retarding passage between said suction

chamber and said vacuum chamber and adapted to be normally filled with liquid to resist pressure equalization under conditions of slow leak from the distributing system 5 until the pressure change developed releases the restraining action of said retarding device and thereupon allows a sudden fluid

impulse to be generated in said suction chamber.
